UNITED STATES PATENT OFFICE.

ARTHUR W. BROWNE, OF PRINCE BAY, NEW YORK, ASSIGNOR TO THE S. S. WHITE DENTAL MANUFACTURING COMPANY, OF PHILADELPHIA, PENNSYLVANIA.

DENTAL CHAIR.

No. 873,015.

Specification of Letters Patent.

Patented Dec. 10, 1907.

Application filed September 19, 1906. Serial No. 335,189.

To all whom it may concern:

Be it known that I, ARTHUR W. BROWNE, a citizen of the United States, residing at Prince Bay, in the county of Richmond and State of New York, have invented certain new and useful Improvements in Dental Chairs; and I do hereby declare the following to be a full, clear, and exact description of the invention, such as will enable others skilled in the art to which it appertains to make and use the same.

My invention relates to hydraulic supporting and elevating mechanism particularly designed for dental chairs, my object being to improve such mechanism in several particulars.

The present invention consists of certain improvements fully described in the following specification in connection with the accompanying drawings, and pointed out in the claims at the conclusion of said specification.

In said drawings, which illustrate a structure embodying my improvements, Figure 1 (Sheet 1) is a view partly in side elevation and partly in central vertical section of the chair base, the pump and its operating connections being omitted in this view to avoid confusion, and the extensible column being partly extended. Fig. 2 (Sheet 1) is a view of said base in vertical central section on the line 2—2 of Fig. 4. Fig. 3 (Sheet 2) is a view in central vertical section on the line 3—3 of Fig. 4, some of the parts being omitted and the extensible column being extended almost to its highest elevation. Fig. 4 (Sheet 3) is a top or plan view. Fig. 5 (Sheet 3) is a view in horizontal section on the line 5—5 of Fig. 1. Fig. 6 (Sheet 3) is a view in horizontal section on the line 6—6 of Fig. 1. Fig. 7 (Sheet 1) is a partial view in vertical section showing the pump and the rigid guide projection 25. Fig. 8 (Sheet 1) is a partial view in vertical section showing the opposite or adjustable guide projection 26. Fig. 9 (Sheet 4) is a view on a larger scale than the preceding views of the lowering valve operating mechanism, showing the valve closed. Fig. 10 (Sheet 4) is a similar view showing the valve open. Fig. 11 (Sheet 4) is a view with the parts in the same position as in Fig. 9, but turned at a right angle thereto. Fig. 12 (Sheet 4) is a partial view similar to Fig. 11 but showing the valve open. Fig. 13

(Sheet 4) is a plan view of the lowering valve. Fig. 14 (Sheet 2) is a view of the inner face of the lever forming part of the lock between the rotatable supporting cylinder and pedestal.

The supporting and elevating mechanism, which may be regarded as the base portion of a dental or other chair, as usual in chairs of the type to which my invention belongs, comprises a stationary or non-rotating pedestal 1 provided with a closed bottom 2 and an annular or disk portion 3 for resting upon the floor; a supporting cylinder 4 rotatably mounted in the pedestal; an extensible chair-body supporting and elevating column 19, 20 and 21, and mechanism contained in said supporting cylinder 4 for elevating and lowering said column.

The first part of my invention to be herein described is the improved lock between the pedestal 1 and the rotatable supporting cylinder 4 for locking said cylinder and the chair mounted upon the supporting column against rotation. The cylinder is supported in the pedestal by means of an annular shoulder 5 resting upon the top of said pedestal, upper and lower bearing surfaces 6 and 7 being also provided between the cylinder and pedestal. The lock, best shown in Figs. 3 and 14 (Sheet 2) consists of a lever 8 placed vertically between the pedestal and cylinder in a recess 9 of the latter, the lower end of the lever bearing at 10 upon the cylinder, while near its upper end it bears upon the upper bearing 6 of the pedestal. A headed screw-bolt 11 passes loosely through an opening 12 in the lever above the bearing 6 and projects outside the base through an opening or bearing in the dome or upper part 14 of the cylinder. The outer end of the screw-bolt is engaged by an operating handle or lever 15, by means of which the lever 8 may be drawn against the pedestal and the cylinder and chair-body securely locked against rotation. A very slight movement of the operating handle or lever 15 is required to clamp or release the cylinder. It will be observed that the lever 8 is held in position solely by the screw-bolt 11, the lever not being connected in any other way either to the pedestal or cylinder. On the inner face of the lever 8 is a series of notches 16 (see Fig. 14) to be engaged by a lug or lugs formed in this instance by a pin 17 passed through the screw-bolt.

This construction affords means for adjusting the operating lever 15 to different positions. If desired a light plate spring 18 may be employed for yieldingly holding the lever in proper position, the lower bent end of the spring engaging a notch in the lever and its upper end bearing upon the screw-bolt.

The improved extensible chair-body supporting column consists of a main section 19, 10 a fixed section or cylinder 20 rising from the bottom of the supporting cylinder with which it has rigid connection, and a plunger 21, upon the upper end of which the chair-body is mounted by way of a cross-head or 15 yoke, not shown. The main section 19 is elliptical in cross-section and is divided into two parallel cylinders 22 and 23, the fixed section or cylinder 20 entering the cylinder 22 and the plunger section 21 being fitted in 20 the cylinder 23.

A peculiarity of the main section 19 of the supporting column is that it has bearing in the supporting cylinder at only two points which are diametrically opposite each other 25 on the flat side of the ellipse midway the long axis thereof. In the present instance these bearings consist of preferably half round longitudinal grooves 24, 24, one on each side of the main section, which are engaged by corresponding 30 projections 25 and 26 of the supporting cylinder, the upper end of which is contracted into a neck portion 27 elliptical in cross section to correspond with the cross section of the main section of the supporting column. The projections 25, 26, must be formed on some part of or have some connection with the supporting cylinder and at least one of said projections should be movable or adjustable toward and away from the 35 column, in order to hold the column with sufficient firmness while permitting it to slide freely up and down, and also to provide for wear of the parts. The preferred manner of supporting said projections is to form them 40 upon plates 28 and 29 cast integral with the cylinder. One of said plates (28) is cast rigid with the cylinder and is therefore immovable, but the other (29) is connected with said cylinder only at its opposite ends, the 45 top and bottom being disconnected from the cylinder, whereby said plate has a limited amount of flexibility, sufficient, however, for the purpose in view. Screws 30, 30 serve to regulate the position of the plate and projection carried thereby, thus securing the proper amount of friction between the column and cylinder. If desired the plate 29 or the projection 26 may be made adjustable in some 50 other manner.

60 The plunger 21 is formed with a half round longitudinal groove 31 in which fits a correspondingly shaped projection carried by the main section 19 of the column. This projection (see Fig. 3, Sheet 2) may consist of a

block or shoe 32 half round in cross section 65 and provided with a rounded projection 34 seated in the socket of an adjustable bearing formed by a screw 33 in the main section 19.

Suitable packing 35 is placed between the fixed cylinder 20 and the cylinder 22 of the 70 main section of the column, and also at 36 between the plunger 21 and the cylinder 23 of said main section. The upper end of the cylinder 22 is closed by a screw plug 37 and the lower end of the cylinder 23 is closed by a 75 screw cap 38. Communication between the two cylinders 22 and 23 is afforded by a passageway 39 at the lower end of the main section of the column. The fixed cylinder 20 communicates by way of a passage 40 with a 80 pump indicated at 41, which is operated by an external foot lever 42.

Oil may be introduced to the base through an opening in the plug 37, which opening is closed by a screw 43. By operating the 85 pump oil is forced into the fixed cylinder 20 and from thence into the cylinder 22 and next into the cylinder 23, with the result of projecting or extending the column. That is to say, the main section 19 is projected upwardly in the supporting cylinder 4 and the plunger 21 is projected upwardly in said main section. By opening a lowering valve, further on to be explained, the column and the chair-body carried thereby may be lowered.

The pump (see Figs. 2 and 7, Sheet 1, and Fig. 6, Sheet 3) consists of an upright cylinder 41, a hollow piston 44, a piston rod 45, a rocking arm 46, a rockshaft 47 to which said arm is rigidly connected, the before-mentioned operating foot lever 42, and a spring 48 for returning the parts to their normal position. The rocking arm 46 is mounted in bearings in the dome 14 of the supporting- 105 cylinder 4, and in order that the rockshaft may be quickly and easily assembled and at the same time a strong durable connection be provided, the construction is as follows: The operating foot lever 42 and the rockshaft 47 110 are integral, while the arm 46 is a separate piece. (See Fig. 6, Sheet 3.) This arm 46 is formed at one end with a head 49 having bearing in the supporting-cylinder and provided with an opening 50 in which the reduced end 51 of the rockshaft 47 is snugly fitted. Formed on the opposite end of the rockshaft is a journal 52 having bearing in the supporting-cylinder and corresponding to the journal formed by the head 49 of the 120 arm 46. A lug 53 on the arm 46 engaging a notch or socket in the rockshaft causes said rockshaft and arm to move as one, while a screw 54 securely binds the two together. The parts are readily assembled by first placing the arm in position, then inserting the rockshaft through the bearing of cylinder 4 and through the opening 50 of the arm until 125

the lug 53 is seated in the rockshaft notch, and finally placing the screw 54 in position.

The outlet, lowering or trip valve mechanism will now be described, reference being made particularly to Figs. 1 and 2, Sheet 1, Fig. 6, Sheet 3 and Figs. 9, 10, 11, 12 and 13, Sheet 4. An outwardly opening coned valve 57 is located in a passageway at the lower end of the fixed cylinder 20, the valve being connected to a bell-crank lever 58 fulcrumed at 59, a stiff coiled spring 60 serving to normally close the valve against pressure of the oil in the fixed cylinder. A rod 61 resting in a depression 62 on the top of the bell-crank 10 lever 58 is connected at its upper end at 66 to an arm 63 fast upon a rockshaft 64 having bearing in the supporting cylinder 4. This rockshaft projects outside said cylinder 15 above the pedestal 1 and has there connected with it an operating or trip lever or handle 65 designed to be actuated by the foot. Normally the trip valve is closed by reason of the spring 60, but by slightly moving the trip lever to one side the rod 61 is depressed, thus 20 rocking the bell-crank lever 58 and opening the valve against the pressure of the spring 60, whereby the oil is allowed to escape from the fixed cylinder 20 and the column and chair-body allowed to descend.

30 The connection 66 between the rod 61 and arm 63 is so related to the rockshaft 64 that if the trip lever 65 is moved far enough to cause said connection 66 to pass beyond a line drawn through the center of the rock- 35 shaft and the lower end of the rod 61, the trip valve will be held open until the parts are positively returned to their normal position. The purpose of this is to enable the chair-body to be lowered from its highest to 40 its lowest position by merely pressing the trip lever as far as it will go, and without the necessity of keeping the foot upon said lever. When the trip lever has been pushed far enough to hold the valve open, as just de- 45 scribed, its further movement in this direction is arrested by an arm 67 coming in contact with a fixed stop formed in this instance by a lug 68 on the plate 29 of the supporting cylinder dome. Connected to said arm 67 50 by way of a link 69 is a vertical release rod 70 adapted to project above the supporting cylinder dome. When the trip lever is moved to hold the trip valve open the release rod is thrust upwardly, and when the chair-body 55 reaches its lowest position a lug on the cross-head or yoke (not shown) strikes the release rod, thus automatically closing the trip valve and restoring the trip lever to its normal position. This construction is a simplification 60 of the mechanism shown, described and claimed in my United States Letters Patent No. 713,282, granted November 11, 1902.

The lower end of the release rod 70 may be

made to enter a socket 71 having openings 72, this construction acting as a dash pot for 65 cushioning the downward movement of said rod.

I claim as my invention:—

1. The combination in a chair base, of the pedestal, the supporting-cylinder rotatably 70 mounted therein, a clamping lever placed be- 75 tween said pedestal and supporting-cylinder and bearing near one end upon the former and at or near its opposite end upon the lat- 80 ter, a screw-bolt passing through an opening in said lever at a point above where it bears upon said pedestal and also through an open- 85 ing or bearing in said supporting-cylinder, and an operating handle having threaded connection with said screw-bolt outside said supporting-cylinder.

2. The combination in a chair base, of the supporting - cylinder, an extensible chair- 85 body supporting column, the main section of said column having an elliptical cross-sec- 90 tion, said main section having bearing in the supporting-cylinder at but two points dia- 95 metrically opposite each other on the flat side of the ellipse midway the long axis thereof.

3. The combination in a chair base, of the 90 supporting - cylinder, an extensible chair- body supporting column, the main section of said column having an elliptical cross-sec- 95 tion, centrally disposed longitudinal grooves diametrically opposite each other on the flat 100 sides of said main section, and corresponding projections on said supporting-cylinder, said projections fitting in said grooves.

4. The combination in a chair base, of the 100 supporting - cylinder, an extensible chair- body supporting column, the main section of said column having an elliptical cross-sec- 105 tion, centrally disposed longitudinal grooves diametrically opposite each other on the flat sides of said main section, and corresponding 110 projections mounted upon said supporting- cylinder and fitting said grooves, one of said projections being adjustable toward and away from said main section.

5. The combination in a chair base, of the 110 supporting - cylinder, an extensible chair- body supporting column movable up and down in said cylinder, longitudinal grooves on the exterior of said column, plates integral with said cylinder, one of said plates be- 115 ing slightly flexible or movable toward and away from said column, a projection on each of said plates, each projection fitting a groove in said column, and means for alter- 120 ing the position of said movable plate.

6. The combination in a chair base, of the 125 supporting - cylinder, an extensible chair- body supporting column, the main section of said column having an elliptical cross-sec- tion, centrally disposed longitudinal grooves diametrically opposite each other on the flat

sides of said main section, a pair of plates integral with said supporting-cylinder, one of said plates being slightly flexible or movable toward and away from said main section, a 5 projection on each of said plates adapted to fit in the corresponding groove on the main section, and means for altering the position of said movable plate.

7. In supporting and elevating mechanism 10 for chairs, the combination of an extensible column, mechanism for elevating or extending said column, a normally closed outlet or lowering valve, a bell-crank lever connected to said valve, a rockshaft, an actuating lever 15 connected thereto, an arm also connected to said rockshaft, and a rod connected with said arm and with said bell-crank lever of the outlet or lowering valve.

8. In supporting and elevating mechanism 20 for chairs, the combination of an extensible column, mechanism for elevating said column, a normally closed outlet or lowering valve, a rockshaft, an actuating lever connected thereto, an arm also connected to said 25 shaft, a rod pivoted to said arm and having

connection with said outlet or lowering valve, another arm connected to said rockshaft, and a vertically movable trip rod having connection with said last mentioned arm.

9. The combination in a chair base, of a 30 pedestal, a supporting-cylinder, an extensible column, a pump, a rocking arm having connection with the piston of said pump, said rocking arm being provided with a head at one end having bearing in said supporting cylinder and formed with an opening, a rockshaft having one end fitted in the opening of said rocking arm and having bearing at its opposite end in said supporting-cylinder, an operating-lever rigidly projecting from said 35 rockshaft outside said supporting cylinder, and means for interlocking said rocking arm with said rockshaft.

In testimony whereof I affix my signature in presence of two witnesses.

ARTHUR W. BROWNE.
